(57) **CLAIM**

The ornamental design for a floor polishing armature as shown and described.

DESCRIPTION

FIG. 1 is a top perspective view.

FIG. 2 is a bottom perspective view.

FIG. 3 is a left side view.

FIG. 4 is a right side view.

FIG. 5 is a front view.

FIG. 6 is a back view.

FIG. 7 is a top view.

FIG. 8 is a bottom view; and,

FIG. 9 is a cross section view taken from line 9-9 in FIG. 7.
